UNITED STATES PATENT OFFICE.

WILLIAM F. BRENNAN, OF PROVIDENCE, RHODE ISLAND, ASSIGNOR OF
ONE-FOURTH TO JAMES H. BRENNAN, OF SAME PLACE.

COMBINED WATCH-KEY AND CROSS-BAR FOR WATCH-CHAINS.

SPECIFICATION forming part of Letters Patent No. 274,903, dated April 3, 1883.

Application filed February 12, 1883. (No model.)

To all whom it may concern:

Be it known that I, WILLIAM F. BRENNAN, of the city and county of Providence, in the State of Rhode Island, have invented a certain 5 new and useful Improved Combination of a Watch-Key and Cross-Bar for Watch-Chains; and I declare the following to be a specification thereof, reference being had to the accompanying drawings.

Like letters indicate like parts.

Figure 1 is a longitudinal vertical section of my invention. Fig. 2 is a side elevation of the key portion detached from its sheath and ready for use.

15 My invention is a novel combination of a cross-bar of a watch-chain with a watch-key. It consists of a tubular cross-bar made in two separable parts, to one of which is permanently affixed a stem of a watch-key, and into the 20 other of which said key is inserted and locked therein by the action of a spring, as hereinafter fully specified.

In the drawings, A represents a portion of a cross-bar. It is made tubular, having a hollow knob, a, or other ornamentation at one end, and a hollow band or bead, b, at its open end, to which band b the eye or ring c is fastened, for the attachment of the watch-chain. The remaining portion, B, of the cross-bar consists of a straight tube, closed at one end by the hollow knob a' or other ornamentation, the open end of said tube B being made with a diameter allowing it to snugly fit into the open end of the tubular bar A, as shown in Fig. 1. 30

35 A watch-key, C, is fitted within the open end of the tube B, and fastened thereto by the pin d, thus forming a continuous piece with the tube B, as shown in Fig. 2. A bow-spring, D, bent as shown in Fig. 1, is contained within

40 the tube B, and the stem of the watch-key C, as appears in section in Fig. 1, the bow of said spring passing through slots e e' of the key and tube B, respectively, and projecting slightly beyond and out of said slots, as shown. The 45 spring D thus has a slight vertical play, and can be depressed so as to bring its bow flush with the outer surface of the tube B. When not in use the key portion, Fig. 2, is sheathed in the tube A, the key entering the open end 50 of the tube or sheath A until the spring D en-

gages with the inner surface of the band or bead b, thus locking the parts A B together. To detach the parts, when it is desired to use the key, the tube B is withdrawn from the tube A, and the bow of the spring D is thereby depressed within the slots e e' and the key portion B C is disengaged. When the two parts are connected as described, they form a cross-bar of usual appearance, the key being wholly concealed from view and securely locked in position; but when detached the parts B C form a watch-key, which can be handled and used as freely as a key of common shape and construction. The sheath A covers and protects the key C from dust and other clogging substances with which a common watch-key is liable to be more or less filled, and the insertion of the key in the sheath, as described, is safer and more convenient than carrying it loosely in the pocket or in any other common 60 manner.

Although the style of cross-bar shown in the drawings is best adapted to my invention, any other style may be used which affords an interior tubular space for the insertion of the key 75 and spring and the locking of the parts together.

I do not wish to confine myself to any particular form of spring. I prefer to use a bow-spring, as described; but any other spring having the same function would obviously be a mere equivalent and within my invention.

I claim as a novel and useful invention and desire to secure by Letters Patent—

1. A separable tubular cross-bar made in 85 two parts, held in engagement by a spring, one part carrying a watch-key and the other forming a sheath for said key, substantially as specified.

2. The combined cross-bar and watch-key 90 herein described, consisting of the tube A, having the bead b and ring c, the slotted tube B, provided with the slotted watch-key C, and the spring D, arranged and operating substantially as shown, and for the purpose specified.

WILLIAM F. BRENNAN.
